Specification for Design.

Patented May 20, 1919.

Application filed February 21, 1919. Serial No. 278,549. Term of patent 14 years.

To all whom it may concern:

Be it known that I, FRANK A. WEEKS, a citizen of the United States, residing at Plainfield, in the county of Union and State of New Jersey, have invented a new, original, and ornamental Design for a Loose-Leaf Pad-Calendar Holder, of which the following is a specification, reference being had to the accompanying drawings, forming a part thereof, and in which—

Figure 1 is a perspective view;

Fig. 2 a side elevation on a larger scale, and

Fig. 3 a top view of a loose-leaf pad-calendar holder embodying my design.

I claim:

The ornamental design for a loose-leaf pad-calendar holder, as shown.

FRANK A. WEEKS.
